Primary Examiner — Leanne Was-Englehart

(57) **CLAIM**

The ornamental design for a safety gate for babies, as shown and described.

DESCRIPTION

1.1: is a first perspective view of the safety gate for babies;

1.2: is a second perspective view thereof;

1.3: is a front perspective view thereof;

1.4: is a right perspective view thereof;

1.5: is a left perspective view thereof;

1.6: is a right perspective view thereof;

1.7: is a top perspective view thereof;

1.8: is a bottom perspective view thereof.

The broken lines depict portions of the safety gate for babies that form no part of the claimed design.

1 Claim, 8 Drawing Sheets
